TOOL HOLDER FOR METAL WORKING MACHINES

Filed March 14, 1929

UNITED STATES PATENT OFFICE

WILLIAM BURKART AND FRANK H. PETERSEN, OF DENVER, COLORADO

TOOL HOLDER FOR METAL-WORKING MACHINES

Application filed March 14, 1929. Serial No. 346,880.

Our invention relates to improvements in tool holders for metal-working machines, and more particularly to holders for use in connection with steel tools of maximum hardness. 5 The primary object of the invention is to provide a holder in which the tool is held and supported at every point so that it will not be subjected to uneven strain or pressure, or to vibratory action within the holder, when in 10 use, thereby eliminating the probability of its being broken.

Further, to provide a holder in which the tool is held by clamping pressure which is exerted uniformly throughout the length of the 15 tool along its sides, and in which the cutting end of the tool is supported to withstand the vertical strain exerted against its cutting edge.

A further object of the invention is to provide a holder with improved means for feeding the tool forward therein, as the length of the tool is diminished by wear, and consequent sharpening, and for supporting the tool 20 against inward movement.

25 These, and other objects which will hereinafter appear, are accomplished by the device illustrated in the accompanying drawings in which,—

Figure 1 is a side view of a portion of a 30 metal-working lathe showing the improved tool holder in connection therewith.

Figure 2 is a vertical longitudinal sectional view—full size—through the improved tool holder, showing the tool therein and the improved mechanism for pushing the tool forward and supporting the same against backward movement.

40 Figure 3 is a horizontal sectional view of the holder on the line 3—3 of Figure 2, the tool and the means for pushing the same forward being removed.

Figure 4 is a transverse sectional view of the holder on the line 4—4 of Figure 2.

45 Figure 5 is a sectional view thereof on the line 5—5 of Figure 2.

Figure 6 is a side view of a portion of the main or body member of the holder, the bar which forms the other member being 50 moved.

Figure 7 is a sectional view of the same on the line 7—7 of Figure 6.

Figure 8 is a perspective view of a portion of the bar which forms the other member of the holder. 55

Figure 9 is an end view of the threaded plug forming part of the tool adjusting mechanism, and

Figure 10 is a view of an implement for turning the threaded plug. 60

Our improved tool holder is adapted to hold metal-cutting tools of the hardest character of steel, for use in lathes, planers, shapers, boring-mills and other metal-cutting machines; and our tool holder has been especially invented to hold a German-made steel called "Widia." Tool steel of this name and character is so brittle that when used in the common type of tool post it frequently breaks

70 under the clamping pressure of the set screw in the tool post, for the reason that the clamping pressure under which it is held is not uniformly distributed. In the common type of holder, the tool is inserted in a square hole in the tool-post and is clamped tightly therein by a set screw, and the tool is under greatest pressure at the point where the set screw is turned down against it, and should there be the slightest unevenness either in the bottom

75 of the hole or in the tool, the tool will snap and break into two pieces under the clamping strain at the set screw and the cutting at the cutting edge of the tool. Our improved holder eliminates the probability of

80 breakage by providing an improved manner of clamping the tool, as will now be particularly described.

85 Referring to the accompanying drawings: The numeral 1 refers generally to a metal working lathe, provided with carriage 2, a compound rest 3, a tool post 4, and a cross feed screw 5, all of which parts are of common construction and therefore constitute no part of the present invention.

90 The letter A designates the improved tool holder, which comprises two members, B and C. The member B constitutes the main or body portion of the holder and is preferably about eight inches long, about one inch and

95 five-eighths wide, and about three-quarters of

100

an inch thick. The body is channeled for about three-fourths of its length from its forward end, as shown at 6, and the bottom of the channel terminates at its rear end in an outwardly curved face 7. The member C of the holder is in the form of a bar which fits snugly within the channel 6 and its rear end is curved as shown at 8 to correspond to the curved face 7 of the rear end of the channel. The outer face of the bar C is flush with the corresponding face of the body B, and in the inner face of the bar and near the lower edge thereof is formed a groove 9 which extends parallel with the said lower edge for a little more than half the length of the bar, beginning at its curved end, and then merges into an upwardly-inclined continuation 10 which is at an angle of approximately twenty degrees to the part 9 of the groove, and extends through the forward end of the block. The groove 9-10 is square throughout, and preferably three-eighths of an inch in diameter, and the part 10 of the groove receives the tool D. The forward end of the lower side of the groove 10 extends slightly beyond the bottom thereof, as shown at 11, this extension forming a support for the under side of the projecting end of the tool, as will be understood by reference to Figure 2.

A round hole 12 is formed in the rear end of the body member B and extends through to the channel 6 in said member and in axial line with the groove 9 in the bar C, and this hole is tapped to form an internal thread one-half inch in diameter. Ordinarily, this threaded hole 12 would extend through the curved face 7 of the channel, thereby forming a series of incomplete threads which would serve no purpose. To obviate this, a hole 13 is drilled into the curved face 7 at right angles to the axis of the threaded hole 12, as shown by the dotted circle, thus forming a straight wall 14 at the rear end of the channel 6, through which the threaded hole 12 passes, as will be understood by reference to Figure 6. The bottom of the hole 13 is reamed out, so as to be on a level with the bottom of the channel 6.

The tool D comprises a bar of steel about two and one-half inches long and three-eighths of an inch square, and its cutting end may be half round or any other required shape. The tool is inserted in the inclined groove 10, and in order to insure a uniform support of the tool along its lower and right-hand sides, which are the sides subjected to strain or pressure under cutting action; an angle plate 15 of thin sheet copper is disposed along the bottom and right-hand sides of the tool, as shown in Figures 2 and 5, and this angle plate in a manner cushions the strain upon these sides of the tool, and absorbs any possible vibratory action. The side member of the copper plate contacts with the bottom face of the channel 6 of the body member B

and clamping pressure of the body B and bar C upon the tool is effected by a bolt 16 which passes loosely through a hole in the body member and into a threaded hole in the bar C, the head of the bolt being forcibly turned against the body, thereby clamping the tool between the two parts of the holder. By this means the tool is held under a uniform clamping pressure throughout its length. The curved end portion 8 of the bar is preferably electrically welded to the body member although it may be riveted or otherwise secured thereto, thereby becoming practically an integral part of it, and this arrangement not only secures the bar to the body, but permits a sufficient yielding movement of the remaining portion of the bar within the channel 6 to admit of the clamping action above described.

As the length of the tool is diminished by wear and consequent sharpening, it is moved forward and supported in the groove 10, against backward thrust, in the following manner: A rod or plunger 17 is inserted in the threaded hole 12 and into the groove 9 of the bar C. This plunger is of a length to extend from a short distance from the entrance of the hole 12 to a point about one-half of the length of the groove 9, and between the front end of this plunger and the rear end of the tool are interposed a number of hard steel balls 18. A threaded plug 19 is screwed into the hole 12 against the plunger rod 17 by means of a crank rod 20 having a squared end 21 which enters a square socket 22 in the said plug, or the plug may be turned by an ordinary screw driver, the end of which, when inserted in the socket 22, will engage two diagonally opposite corners of the said socket. By this arrangement, the plunger rod 17 can be screwed forward as the tool diminishes in length, until the forward end of the rod engages the inclined face of the groove 10 during which movement of the rod the balls 18 will pass from the groove 9 into the groove 10, thereby holding the tool against backward movement in the holder until the said tool is too short for further use.

In order to prevent the balls from rolling out of the holder when the tool is removed for sharpening or for the insertion of a different tool, a hole 23 is drilled into the bottom edge of the bar C, at right angles to and in line with the groove 10. A drill having a rounded cutting point is used for this purpose, and when the point of the drill pierces the wall of the slot 10, the drilling is stopped, thus leaving a hole in the wall of the slot 10 of less diameter than the hole 23, thus providing a shoulder 24 in the bottom of the said hole 23. A ball 25 is inserted in the hole 23, a coil spring 26 is then placed in the hole against the ball, and the spring is held under compression by a disk 27, which is screwed into the entrance of the hole against the spring,

the entrance portion of the hole being threaded. When the tool D is removed, the spring 26 will force the ball 25 against the bottom of the hole 23, and the ball will project slightly into the groove 10, but the shoulder 24 will limit its further movement. The projecting part of the ball will thus form a barrier in the slot 10 which will prevent the balls 18 from rolling out of the holder.

10 By the improved type of tool holder herein set forth, the tool is clamped under uniform pressure throughout its length; the thin copper angle plate contributing to this end, and acting to absorb any possible vibration in the 15 tool, and the balls interposed between the plunger rod 17 and the rear end of the tool, act to translate the horizontal thrust of the plunger rod into a thrust in the direction of the angle of the drill, so that the tool is not 20 only held against back thrust, but can be moved forward in the inclined groove until it is too short for further use.

As the bar C is welded at one end to the body member B, it is inseparable therefrom, 25 and therefore the balls 18 must be inserted in the holder through the threaded hole 12, and the balls are of a size to fit snugly but slidably in the groove 9 of the bar, which is closed on one side by the wall of the body member, 30 as clearly shown in Figures 4 and 5.

In operation, the holder is clamped in the tool post of the machine in the usual manner, the tool is placed in the groove 10 of the holder, and the threaded plug 19 is adjusted so 35 that the plunger rod 17 and balls 18 will support the tool in the required position; the tool is then ready for use.

Having described our invention, what we 40 claim as new and desire to secure by Letters Patent, is:—

1. A tool holder of the character described comprising a body member channeled for the greater part of its length, the unchanneled portion having a longitudinal threaded hole 45 therein; a bar in said channel having a horizontal groove in axial line with said threaded hole, which terminates in an upwardly inclined tool receiving groove; a tool therein; means for clamping the body member and 50 bar upon said tool to hold the same in place; a push rod in said threaded hole and extending into the groove in said bar; a threaded plug in the threaded hole for moving the rod forward and holding the same 55 against back thrust; and balls interposed between the rod and the rear end of the tool, to translate the horizontal thrust of the rod into an angular thrust in line with the axis of the tool.

60 2. A tool holder of the character described, comprising a body member channeled for the greater part of its length, the unchanneled portion thereof having a threaded longitudinal hole; a bar in said channel having a 65 horizontal groove in line with the threaded

hole, which terminates in an upwardly inclined tool receiving groove; a tool therein; a thin sheet metal angle plate disposed along the bottom and one side of said tool; a headed bolt which passes loosely through the 70 body member and is in threaded engagement with the bar, for clamping the parts against the tool, thereby to hold the same in place; a push rod disposed in the threaded hole and in the horizontal groove; a threaded plug in the hole for moving the rod forward and holding the same against back thrust, and a series of contacting elements 75 between the rod and the rear end of the tool, whereby the horizontal thrust in the rod is 80 translated into an angular thrust upon the tool in line with its axis as the same is moved forward in its groove, said bar being welded at its rear end portion to the body member.

3. In a tool holder of the character described, a member channeled for the greater part of its length; a bar in the channel, its rear end portion being welded to the channeled member, the unchanneled portion of the member having a threaded longitudinal hole therein and the bar having a horizontal groove in line with the hole, the forward portion of which terminates in an upwardly inclined tool holding groove, a tool in said groove, a push rod disposed in the 90 threaded hole and horizontal groove, a threaded plug in the hole for moving the rod forward and holding the same against back thrust; balls interposed between the rod and the rear end of the tool, to impart the horizontal thrust of the rod to the tool as the same is moved forward in its groove; means 95 for clamping the channeled member and bar upon the tool to hold the same, said bar having a socket therein at right angles to the inclined groove, said socket having a hole in its bottom opening through the adjacent wall of the inclined groove, and of less diameter than the socket; and a spring-actuated ball in the socket, which projects through the 100 hole in the bottom of the socket when the tool is removed, thereby to present a barrier in the inclined groove to prevent the escape of first mentioned balls from the holder.

4. A tool holder of the character described comprising a body channeled for a portion of its length; a bar in said channel, the rear end portion of which is welded to said body, the remaining portion being free, a groove being formed in said bar, registering at one 115 end with a threaded hole in the body, the other end portion of the groove being upwardly inclined and constituting a tool-receiving groove; a tool in said groove, the metal forming the lower side of the tool-receiving groove being extended beyond the entrance to said groove to form a support for the cutting end of the tool; a thin copper angle plate disposed along the bottom and one side of said tool; a clamp bolt extending 120

125 130

loosely through the forward end of the body and in threaded engagement with the bar for clamping the parts upon the said tool; a rod disposed in the threaded hole and in the adjoining portion of the groove; means threaded in the hole for moving the rod and holding the same against back thrust; means interposed between the end of the rod and the tool for transmitting the thrust of the rod to the tool in line with its axis.

10 In testimony whereof, we affix our signatures.

WILLIAM BURKART.
